LIP STICK

Philip A. Reutter, Waterbury, Conn., assignor to
 Scovill Manufacturing Company, Waterbury,
 Conn., a corporation of Connecticut

Application November 14, 1931
 Serial No. 574,942

3 Claims. (Cl. 206—56)

This invention relates to certain improvements in the small metal containers for holding cosmetics and now commonly known as lipsticks or paste holders.

5 In this class of containers it is very important that the parts may be cheaply made, and easily and quickly assembled. It is further important that the completed article be of attractive appearance, and so constructed that the paste stick 10 may be protruded from and retracted into the container, the mechanism for effecting this being of simple form and easily operable by the user.

It is an especial object of the present invention 15 to provide a container of simple form and few parts, cheap to make and assemble, and of attractive appearance.

It is a further object of the invention to provide 20 an improved stick of lip paste or like plastic cosmetic which may be used in this novel container, so that it may be retracted and protruded without injury to the stick.

With these and other objects not specifically referred to, the invention consists in certain novel 25 parts, arrangements and combinations which will be described in connection with the accompanying drawing and the novel features pointed out in the claims hereunto annexed.

In the drawing,—

30 Figure 1 is a side view of the container with the parts in closed position;

Figure 2 is a partly sectional, partly broken away view of the various parts of the container shown disassembled;

35 Figure 3 is a central sectional view of the container shown in Figure 1;

Figure 4 is a sectional view of the paste holding cup, the section being taken on line 4—4 of Figure 2, and

40 Figure 5 is a detail sectional view, the section being taken on line 5—5 of Figure 3.

Referring now to the drawing, the container selected to illustrate the invention is one in which the parts are made of light metal so that they can 45 be readily and cheaply formed, and the container shown is triangular in cross section. It will be understood, however, that the invention is not to be limited to this particular type of container or to a metal container, but that the invention may 50 be embodied in containers of various forms and of materials suitable for the purpose. As shown, however, the container includes an inner casing 1, open at one end, as indicated at 2, and having a bottom 3. This casing 1 has centrally located 55 therein a spiral or screw shaped propelling mem-

ber 4, made of flat stock simply by twisting the metal of the stock, this screw propeller having a flattened outer end 5.

The propeller screw is held in place in any suitable manner and is provided with means for 60 rotating it. As shown, the propeller or screw is provided with a pair of projections or wings 6, 7, and beyond the wings extends through an aperture in the bottom 3 of the casing, and is formed with a head 8 engaging in a recess 9 of a rotary member 10, so that as the rotary member 10 is turned the propeller screw is likewise given a rotary movement. Where the container is triangular in shape, as shown, this rotary member, as shown in Figure 5, is likewise triangular, but is 65 made of a slightly larger size than the outer walls of the casing 1, as indicated at 11 in Figure 2, for purposes hereinafter referred to.

Enclosed within the casing is a stick holding cup 12, which is triangular, as shown in Figure 4, 75 where the container has a triangular shape. This paste holding cup has a bottom 12' provided with an opening 13 to receive the propeller screw 4, before referred to, and this cup is propelled forward and backward by the rotary movement of 80 the screw. While the connections between the screw and the cup may be of various characters to permit this movement, in the particular construction shown the hole 13 in the cup is relied on for this purpose and, as illustrated, this hole 85 is formed with centrally converging side walls, as indicated at 14, so as to give in effect a butterfly shape. The flattened end 5 of the screw may be readily passed through the hole 13, but upon rotation of the screw the screw engages the side 90 walls 14 and effects a traveling movement of the cup. The parts are or may be enclosed by an outer casing 15, which extends downwardly and encloses the inner casing 1, as clearly shown in Figure 3. The edges of the inner end of the 95 casing 15 and the edges of the rotary member 10 are slightly rounded, to leave a slight gap 16, to enable the inner casing to form a finger grip, whereby the outer casing may be removed from the inner casing and its associated parts, when 100 it is desired to use the holder.

In accordance with the invention, it will be seen that this construction is of few parts, and can be readily and cheaply made and quickly assembled, the propelling mechanism simply consisting of the screw, made of flat metal, and the revolving head. Where, however, a screw type of propeller is employed for protruding and retracting the stick of paste material, it is desirable that this material be so carried in the holder 110

that it will not be engaged by the propelling parts, so that injury to the paste stick is avoided. The present invention therefore will include an improved stick of paste, marked 17. This paste stick is formed, preferably by moulding, of a dimension to snugly fit the cup 12, but to be free of the inner wall of the casing 1, as indicated at 18 in Figure 3, so that there is no friction between the casing 1 and the stick. This stick, furthermore, is formed, preferably by moulding, with a longitudinal opening or recess 19, of slightly greater length and slightly larger diameter than the screw propeller 4, so that the screw propeller, upon rotation, does not come in contact with the paste. It will be seen therefore that the stick may be protruded and withdrawn from the casing 1, after the cover 15 has been removed therefrom, without the stick coming in contact with any of the propelling parts of the mechanism. Thus a cheap screw threaded propeller may be used without in any way injuring or deforming the stick of paste material.

It will be understood that while the invention has been described as a container for lip paste, other plastic cosmetic substances, such as shaving sticks or the like, may be used with this container.

It will be seen with the construction shown and described that a very simple and efficient holder has been provided in which the stick can be protruded and retracted as desired without injury to the stick, and a stick and container have been provided which may be readily and quickly made and assembled.

While the construction selected to illustrate the

invention is a preferred one, it will be understood that various changes may be made in the configuration of the container and in the form and arrangement of the parts without departing from the invention as defined in the appended claims.

80

What is claimed is:

1. A holder for a stick of cosmetic material comprising a shell, a stick-receiving cup slidable in said shell but held against rotation with respect thereto, said cup having a centrally positioned elongated slot, and means for advancing and retracting said cup including a turn-button rotatably mounted on the rear end of the shell so as to be held against movement longitudinally thereof, and a twisted flat strip secured at its rear end to said turn-button and passing through said slot.

85

2. A holder for a stick of cosmetic material comprising a shell, a stick-receiving cup longitudinally movable in the shell and having an elongated opening in its lower end, a twisted flat strip extending through said opening for propelling said cup, and an operating head connected with one end of said propelling strip for rotating the same.

90

3. A holder for a stick of cosmetic material comprising a shell, a stick-receiving cup longitudinally movable in the shell and having an elongated opening in its lower end, a twisted flat strip extending through said opening for propelling said cup, and an operating head connected with one end of said propelling strip for rotating the same, the other end of said strip being flat and untwisted.
